UNITED STATES PATENT OFFICE.

SILAS N. DODD, OF TOLEDO, IOWA.

HATCHING AND BROODING COOP.

Application filed September 12, 1923. Serial No. 662,253.

To all whom it may concern:

Be it known that I, SILAS N. DODD, a citizen of the United States, and a resident of Toledo, in the county of Tama and State of 5 Iowa, have invented a certain new and useful Hatching and Brooding Coop, of which the following is a specification.

The object of my invention is to provide an improved hatching and brooding coop of 10 comparatively simple, durable and inexpensive construction adapted to be used in connection with hatching and raising poultry.

More specifically it is the object of my invention to provide an improved coop of 15 such size and shape that a single hen may be housed for the purpose of hatching and raising her brood of chickens, the coop being so arranged that it may be placed at any desired place in the yard and so constructed 20 that it may be first used for hatching purposes, then for brooding the small chickens to protect them from the weather and small animals during the brooding stage.

My invention consists in the construction, 25 arrangement and combination of the various parts of the device, whereby the objects contemplated are attained, as hereinafter more fully set forth, pointed out in my claims, and illustrated in the accompanying drawings, 30 in which:

Figure 1 is a side elevation of my improved coop.

Figure 2 is a plan view of the same with the cover of the coop removed.

Figure 3 is an end elevation of Figure 1.

Figure 4 is a vertical, sectional view taken on the line 4—4 of Figure 3.

Figure 5 is a detail plan view of the drinking fountain, showing a portion of the 40 frame in which it is mounted in section.

Figure 6 is an end elevation of Figure 5.

My improved coop has substantially the shape of a small building having a floor member 10 supported on base members 11. 45 The coop is provided with side walls 12 and end walls 13 and 14. The said side and end members are provided with a roof 15. The said coop is preferably constructed of wood. The side and end members are secured together by means of screws 16.

The upper end of each of the end members is provided with ventilating openings 17. A door 18 is hinged to the lower edge of the end member 13 by means of hinges 19. The lower edge of the door 18 is designed to swing outwardly and upwardly

and to be supported in substantially a horizontal position by means of a chain 20, one end of which is secured to the upper portion of the end member 13, the lower end of the chain being secured to the door 18 by means of a hook 21. This provides means whereby the door may be swung either in a horizontal position or in any desired inclined position so as to support the door entirely open or 65 partially open. When the door 18 is moved to a closed position the entire end of the coop is closed.

I have also provided a screen door 22 which is pivoted beneath the lower edge of 70 the member 13 and between the walls 12 by means of pivots 23. The door 22 is of a width less than the door opening formed beneath the lower edge of the member 13. A passageway 24 is provided beneath the 75 lower edge of the door 23 when the said door is in a closed position. The said screen door 22 provides ventilation for the coop in warm weather, and at the same time permits the young chickens to pass in and out 80 through the opening 24.

The lower edge of the door 22 is provided with an eyelet 25 by means of which the door 22 may be swung to a horizontal position beneath the door 18 when the said door is also in a horizontal position, as clearly shown in Figure 1. The eyelet 25 is secured in a hook 26. This permits the coop to be entirely opened to provide means whereby the attendant may have access to the interior 85 of the coop, or to permit the hen to leave and enter as she wishes.

Secured to the left hand base member shown in Figure 4, I have provided a runway 27 pivotally mounted to the said member 11, and of such width that it may be swung to a vertical position to cover the opening 24, with the outer end of the door or runway 27 overlapping the lower end of the door 22. This provides means for closing 90 the left hand end of the coop to prevent the small chickens from entering or leaving, and at the same time have sufficient ventilation through the screen 22. In stormy weather, the door 18 may be lowered in which case 95 the runway 27 is moved to its lower position, as shown in Figure 4, at which time the said door 18 forms a complete enclosure for the left hand end of the coop, as shown in Figures 1 and 4. The member 14 is also formed narrow so as to provide a door opening 29 100 beneath it. The lower edge of the member 105

110

14 is provided with a hinged door 30 for closing the opening 29, said door being capable of being elevated to a horizontal position.

5 Adjacent to the sides of the opening 29 I have provided screen frames 31 which are secured to the outer faces of the members 12 by means of screws 32 in such a manner that the screens may be detachably secured in 10 position, with their lower edges on the ground in such a manner as to form a runway or yard between them, the yard being provided with an outer end member 33, which is also formed of screen.

15 The screens 31 are of a width substantially equal to the distance between the lower edge of the member 14 and the ground surface, so that the upper edge of the screens are substantially in line with the door 30

20 when it is in its horizontal and open position. This provides means whereby the said door 30 may be utilized as part of the cover for the yard. The remaining portion of the top of the yard is provided with a 25 screen 34 which is also screwed into position. All of the said screens are provided with suitable frame so that they may be detachably connected with each other for the purpose of packing them while shipping.

30 It may be mentioned also that the side members 12, and the end members 13 and 14 and the top portion 15 are also screwed together for the same purpose.

35 The door 30 is designed to swing downwardly between the members 31 so that the opening 29 may be closed if so desired, the door 30 being supported in its elevated position by means of a turn buckle 35, one end of which is pivotally secured to the door 30 40 while the opposite end is designed to rest on the inner end of the frame 34.

I have provided a drinking fountain shown in detail in Figures 5 and 6, which 45 comprises substantially a rectangular tank 36 formed very shallow, of a depth substantially equal to the thickness of the frame members of the screens 31. One end of the tank 36 is provided with extending ears 37 pivotally connected to members 38 secured to the upper edge of the lower one of the frame members of one of the screens 31, said frame member being designated by the numeral 39 in Figure 6.

55 The tank 36 is so arranged that it will fold into the position shown in dotted lines in Figure 6, with its open side adjacent to the screen wire.

For supporting the outer edge of the tank 36, I have provided pivoted legs 40 so arranged that when the tank is moved to its 60 lower position, the legs will swing to a vertical position and rest on the ground surface, supporting the tank in a horizontal position. The tank may be filled with water 65 by opening the door 30. The said tank is

positioned beneath the said door, as clearly shown in Figure 1.

A runway 41 is provided for the opening 29, one end of which is designed to rest on a cleat 42 and the opposite end on the 70 ground.

For nesting purposes I have provided a rectangular box or frame 43 having end members 44 and side members 45, the said box being of a length substantially equal to the width of the coop or the space between the walls 12. The box 43 may be moved longitudinally in the coop in any desired position, either located centrally or at either end. After the chickens have been hatched, the nest 43 may be entirely removed if so desired.

Thus it will be seen that I have provided a chicken coop of comparatively simple, durable and inexpensive construction, which may be constructed and built in a factory as a knock-down construction, and which may be easily and quickly assembled when it is desired to use the same, the coop being adapted to first hatch the eggs, the hen being permitted to use the runway provided by the screens 31 to give her the desired exercise. After the eggs have been hatched, the nest may be removed and the coop utilized for brooding purposes, the little chickens being permitted to use the runway provided at the right hand end of the coop or permitted to use the opening 24.

By providing the floor 10 supported on the members 11, it will be seen that a comparatively dry place will be provided for the hen and chickens during the wet and stormy weather.

I claim as my invention:

1. A coop formed with side and end members and having a suitable roof, the end members being formed narrow to form a door opening beneath them, the coop being provided with an elevated bottom; a door hinged to the lower edge of each of the end members designed to swing from an open horizontal position to a closed vertical position, means for adjustably supporting one of the doors in its elevated position, a screen door pivotally mounted in one of the door openings adapted to swing from a vertical position, to a horizontal position, and means for supporting said screen door in its horizontal position beneath the first said door which is adjustably mounted, said screen door being shorter than the opening in which it is mounted for the purpose of providing a passageway beneath it when closed.

2. A coop formed with side and end members and having a suitable roof, the end members being formed narrow to form a door opening beneath them, the coop being provided with an elevated bottom, a door hinged to the lower edge of each of

the end members designed to swing from an open horizontal position to a closed vertical position, means for adjustably supporting one of the doors in its elevated position, a
5 screen door pivotally mounted in one of the door opening adapted to swing from a vertical position to a horizontal position, means for supporting said screen door in its horizontal position beneath the first said door which is adjustably mounted, said screen door being shorter than the opening in which it is mounted for the purpose of providing a passage way beneath it when closed, and a pivoted runway adjacent to
10 the lower edge of the last said door opening, said runway being adapted to swing to a vertical position to close the opening provided beneath the said screen door.

3. A coop formed with side and end members and having a suitable roof, the end members being formed narrow to form a door opening beneath them, the coop being provided with an elevated bottom, a door hinged to the lower edge of each of the
25 end members designed to swing from an open horizontal position to a closed vertical position, means for adjustably supporting one of the doors in its elevated position, a

screen door pivotally mounted in one of the door openings adapted to swing from a vertical to a horizontal position, means for supporting said screen door in its horizontal position beneath the first said door which is adjustably mounted, said screen door being shorter than the opening in which it is mounted for the purpose of providing a passageway beneath it, a pivoted runway adjacent to the lower edge of the last said door opening, said runway being adapted to swing to a vertical position to close the opening provided beneath the said screen door, screen frames mounted to form a yard communicating with the other one of said door openings of said coop, said screens being detachably secured to said coop and to each other, and comprising side members and one end member, the said screens being so arranged that one of the door openings for said coop will swing upwardly between them to a position to form a cover for closing the top of said yard, a cover member for the remaining portion of said yard and means for locking the door in position to form a cover for said yard.

Des Moines, Iowa, August 7, 1923.

SILAS N. DODD.
